Primary Examiner — Sheryl Lane*Assistant Examiner* — Ieisha N Price(74) *Attorney, Agent, or Firm* — Husch Blackwell LLP;
Bryan D. Stewart(57) **CLAIM**

The ornamental design for the low profile staple, as shown and described.

DESCRIPTION

FIG. 1 is a perspective view of a low profile staple;
 FIG. 2 is a front view of the low profile staple;
 FIG. 3 is a back view of the low profile staple;
 FIG. 4 is a right side view of the low profile staple;
 FIG. 5 is a left side view of the low profile staple;
 FIG. 6 is a top view of the low profile staple; and,
 FIG. 7 is a bottom view of the low profile staple.

1 Claim, 5 Drawing Sheets(56)
